MEMORIAL LAMP OR SIMILAR ARTICLE

Robert J. Rettman, Pittsburgh, Pa., assignor to Jas. H. Matthews & Co., Pittsburgh, Pa., a corporation of Pennsylvania

Application January 21, 1958, Serial No. 49,338

Term of patent 14 years

(Cl. D48—20)

Fig. 1

I claim:

The ornamental design for a memorial lamp or similar article, substantially as shown.
